Primary Examiner — Kelley Donnelly(74) *Attorney, Agent, or Firm* — Leanne Taveggia Farrell; Westman, Champlin & Koehler, P.A.**CLAIM**

The ornamental design for a display fixture, as shown and described.

DESCRIPTION

FIG. 1 is a perspective view of a display fixture with environment showing our new design;

FIG. 2 is a perspective view thereof without environment;

FIG. 3 is a front view thereof;

FIG. 4 is a back view thereof;

FIG. 5 is right side view thereof, the left side view being a mirror image;

FIG. 6 is a top view thereof; and,

FIG. 7 is a bottom view thereof.

The broken lines shown in the drawings are included for purposes of illustrating environment or portions of the display fixture and form no part of the claimed design.
